UNITED STATES PATENT OFFICE.

HENRY K. KISO, OF NEW YORK, N. Y.

LETTER-FILE.

1,240,058.

Specification of Letters Patent. Patented Sept. 11, 1917.

Application filed June 3, 1916. Serial No. 101,438.

To all whom it may concern:

Be it known that I, HENRY K. Kiso, a citizen of the Dominion of Canada, and a resident of the city of New York, borough 5 of Manhattan, in the county and State of New York, have invented a new and Improved Letter-File, of which the following is a full, clear, and exact description.

This invention relates to letter files and 10 has for an object the provision of an improved construction and arrangement whereby letters may be properly held together and segregated when placed in a cabinet.

Another object in view is to provide a file 15 in which the sides are formed with folded portions whereby the file may be readily expanded without bowing the front or back, this arrangement being associated with an end having notches for accommodating the 20 folded portion of the sides.

A still further object in view is to provide a letter file in which means are provided for securing the letters in position and also an extension or name tab arranged on part of 25 the file which extends beyond the remaining part so that when the file is in a cabinet the name will extend above the file.

A further object is to provide a file in 30 which bendable securing fingers are connected to the back of the file and readily operated so as to be forced through the letters arranged in the file.

In the accompanying drawing:

Figure 1 is a perspective view of a letter 35 file inclosing an embodiment of the invention.

Fig. 2 is a perspective of the holder shown in Fig. 1 the same being unfolded.

Fig. 3 is a perspective view of the upper 40 part of a slightly modified form of holder to that shown in Fig. 2.

Fig. 4 is a perspective view of the upper part of the holder shown in Fig. 3, a number of letters being shown secured thereto.

Fig. 5 is a perspective view of the holder 45 shown in Fig. 1 arranged to disclose the bottom and the notches formed therein.

Referring to the accompanying drawing by numerals, 1 indicates the back of the 50 holder and 2 and 3 the sides. The sides are connected to the back by V-shaped structures 4 and 5 which allow for expansion of the holder for accommodating a comparatively large number of letters without either the 55 front or back becoming rounded. In order to accommodate these members 4 and 5 the

bottom member 6 is provided with notches 7 and 8 so as to receive the V-shaped members 4 and 5, as more clearly shown in Fig. 6. The member 6 is connected with a bottom flap 9 which is folded over the bottom edge of the letters 10 before the sides 2 and 3 are moved to a closed position.

Eyelets 11 and 12 are positioned in the back 1, said eyelets accommodating the cord 65 13 which also extends through the letters 10 and secures or holds these letters in place. The loose ends of the cord 13 may be secured together by a knot or by a specially constructed member as shown in Fig. 2, the particular structure of this member not forming any part of the present invention.

The inner face of the sides 2 and 3 are provided with spaces 14 and 15 for receiving any desired information, side 3 being 75 also provided with lines 16, 17 and 18, line 16 being arranged on the projecting tab 19 so as to appear above the remaining part of the device when folded, as shown in Fig. 1. Any suitable information may be arranged 80 on lines 16, 17 and 18 and also spaces 14 and 15, as these spaces are provided for receiving information especially adapted for the particular business to which the holder is put. In order to insure that the sides 2 and 3 remain closed fastening eyelet members 20 are 85 connected to the outer face of the sides 2 and 3 and a cord 21 associated therewith for holding the parts folded. The back 1 may be provided with an upper flap 9', if desired, which is constructed similar to the lower flap 9. This arrangement of flaps at 90 each end of the body 1 will prevent loose papers in the folder from becoming accidentally lost and will allow the proper filing 95 of loose letters. When fastening means are used, as for instance, cord 13, the flap 9' may be omitted or used as preferred.

In Figs. 3 and 4 will be seen a slightly modified form of the invention, in which 100 eyelets 22 and 23 are used for clamping in position the bendable fingers 24 and 25, said eyelets extending through said fingers and firmly clamping the end of the fingers to the back 1. When this form of the device is in 105 use the letters 10' are perforated and the fingers 24 and 25 thrust therethrough and bent over as shown in Fig. 4.

What I claim is:

1. A letter file comprising a back, a flap 110 arranged at each end of said back, a foldable structure arranged between each of said

flaps and said back, a pair of side members, a foldable connecting member arranged between each of said side members and said back, and a legend receiving extension projecting from one end of one of said side members.

2. A letter file comprising a back, an end

flap, a pair of side members connected with said back, one of said side members having an extension, an indicating line arranged on said extension for receiving a designating legend, and means for holding the side members in position when folded.

HENRY K. KISO.

Copies of this patent may be obtained for five cents each, by addressing the "Commissioner of Patents, Washington, D. C."
